(57) **CLAIM**

The ornamental design for security key pad with fingerprint identification, as shown and described.

DESCRIPTION

FIG. 1 is a top view of the device.

FIG. 2 is a bottom view of the device.

FIG. 3 is a view of the left edge of the device.

FIG. 4 is a view of the top edge of the device.

FIG. 5 is a view of the bottom edge of the device; and,

FIG. 6 is a perspective view of the device.

1 Claim, 3 Drawing Sheets

FIG. 3

FIG. 4

FIG. 5

FIG. 6
